UNITED STATES PATENT OFFICE

91,991

DESIGN FOR AN ANIMAL FIGURE OR SIMILAR ARTICLE

Walter E. Disney, Los Angeles, Calif.

Application December 30, 1933, Serial No. 50,268

Term of patent 14 years

To all whom it may concern:

Be it known that I, WALTER E. DISNEY, a citizen of the United States, residing at Los Angeles, in the county of Los Angeles and State of California, have invented a new, original, and ornamental Design for Animal Figure or Similar Article, of which the following is a specification, reference being had to the accompanying drawing forming a part thereof.

The figure is a front perspective view of an animal figure showing my new design.

I claim:

The ornamental design for an animal figure or similar article, substantially as shown.

Signed at Los Angeles, Calif., this 12th day of December, 1933.

WALTER E. DISNEY.
